D. R. NICHOLS

FOLDABLE SEAT

Filed Feb. 10, 1927

INVENTOR
D. Randall Nichols
BY J. H. Gibbs
ATTORNEY

UNITED STATES PATENT OFFICE.

DANIEL RANDALL NICHOLS, OF BERWICK, PENNSYLVANIA, ASSIGNOR TO AMERICAN CAR AND FOUNDRY COMPANY, OF NEW YORK, N. Y., A CORPORATION OF NEW JERSEY.

FOLDABLE SEAT.

Application filed February 10, 1927. Serial No. 167,239.

Reference is had to the accompanying drawings which illustrate the preferred form of the invention, though it is to be understood that the invention is not limited to the exact 5 details of construction shown and described, as it is obvious that various modifications thereof within the scope of the claims will occur to persons skilled in the art.

In said drawings:

10 Fig. 1 is a top plan view of the device, shown in position in a compartment of a car, the compartment being shown in section;

Fig. 2 is a view taken on the line 2—2 of Fig. 1;

15 Fig. 3 is a view taken on the line 3—3 of Fig. 1, and

Fig. 4 is a view taken on the line 2—2 of Fig. 1, showing the seat in its lowered position.

20 It is the primary object of this invention to provide a foldable seat for use in railway cars, more particularly such types of cars as are used with elevated railways and the like by motormen.

25 Another object of the invention is to provide a motorman's seat which may be easily raised to position and as easily thrown out of position.

Another object of this invention is to provide a seat for the use of motormen of cars 30 which is formed of few parts and may be easily and readily constructed and which is strong and durable in operation.

Other objects and advantages of this invention will be apparent from the following description taken in conjunction with the accompanying drawings forming a part hereof.

Referring now more particularly to the drawings, in Fig. 1 the numeral 1 indicates 40 the motorman's compartment of a standard elevated railroad car or the like which is defined by means of the partition 2, which is usually formed of sheet steel, and a door 3 to permit ingress and egress into and out of said compartment.

45 As shown more clearly in Fig. 3, the device of the present invention includes supporting elements 4 which are preferably L-bars and said supporting elements are attached to the partition 2 by rivets 5 or the like. These supporting elements 4 are spaced from each other as shown, and receive between them the seat 6 which is formed of the frame 7 and the

cushion 8, the latter being secured to said frame 7 by any suitable means, such as bolts 55 9. Secured to the partition 2 at a point above the seat 6 is a cushion back member 10 which is retained in its connected position with the partition 2 by suitable locking elements 11 and 12, respectively.

60 The frame 7 of the seat 6 is provided near its forward end with pivot means which are shown as a bolt 13 having a nut 14 on the end thereof and said bolt carries a spacer 15. Received between the spacer and the head of the bolt 13 is one end of a seat hanger 16 which is provided with an elongated slot 17 in the lower end thereof, the upper end of said hanger being pivoted to the supporting element 4 by means of a bolt 18 or the like. I 65 have described only one of the connections between the supporting element 4 and the seat but it is to be understood that the supporting means on the other side of the seat is identical with that just described and consequently no further description seems to be necessary.

70 The rear end of the seat 6 is provided with pivots 19 which work in a slotted guide 20 formed in the supporting element 4. As 75 clearly shown in Fig. 2, this guide is provided with a hook-shaped end 21 and its lower end is offset as shown at 22.

75 The seat 6 is provided with a handle member 23 secured to the rear thereof and extending upwardly to a position such that it 80 may be readily grasped to operate the seat.

In use the seat 6 is normally positioned as shown in Fig. 2 and from this figure it can be seen that the seat 6 is retained in its 85 extended position by means of the hangers 16 with the pivots 19 engaged in the offset portion 22 of the guide 20. When it is desired to lower the seat when the same is not in use, the handle 23 is grasped and by a slight 90 outward movement of the seat the pivot 19 will ride out of the offset 22 and upwardly into the hook-end 21, through the guideway 20 and the pivots 19 will support the seat 95 in its lowered position by coming to rest in said hook-shaped portion of the guide. It will be apparent that to bring the seat to its extended position as shown in Fig. 2, an operator merely elevates the seat by means of the handle 23, thus permitting the pivots 100 19 to enter the guide 20 and pass downwardly

until they come to rest in the offset 22, while at the same time elevating the forward portion of the seat.

What is claimed is:

- 5 1. In a foldable seat, means for supporting the same comprising supporting elements, seat hangers secured to said elements and provided with a lower slotted end, pivots secured to the seat adjacent the front end thereof and engaged in said slots whereby relative movement between the seat and hangers is permitted, a guideway formed in said supporting elements and terminating at its lower end in an offset portion and at its upper end in a recess, and pivots secured to said seat adjacent the rear end thereof and cooperating with said guideway whereby when the seat is elevated said pivots are engaged in the offset portions to retain the seat in elevated position, and when the seat is folded the pivots rest in said recesses to suspend the seat in such folded position.
- 10 2. In a foldable seat, supporting elements therefor comprising spaced uprights each

provided with a guideway having the ends 25 thereof inturned to define recesses, a seat, pivots secured to the rear of the seat and working in said guideways, seat hangers pivotally secured to the uprights above the guideways and provided with a slotted forward end, and means pivotally connecting the hangers to the seat through the slots in said hangers.

3. In a seat, spaced uprights each having a guideway formed therein terminating in 35 upper and lower recesses, pivots secured to the rear of the seat and working in said guideway and adapted to rest in the recesses to support the seat in folded or elevated position respectively, and hangers secured to the 40 seat and to the uprights above the guideways, said seat when in elevated position normally urging the pivots to seating position in the lower recesses.

In witness whereof I have hereunto set my 45 hand.

D. RANDALL NICHOLS.
